HOLDER FOR SPRAY CANS OR THE LIKE

Arthur Müller, Kalkbreitestrasse 40,
Zurich, Switzerland

Filed Mar. 10, 1967, Ser. No. 6,160

Term of patent 14 years

(Cl. D62—2)

FIGURE 1 is a perspective view of a holder for spray cans or the like embodying my new design;

I claim:

The ornamental design for a holder for spray cans or the like, as shown.
